BICYCLE LAMP

Eric T. New, Kew Gardens, N.Y.
(1170 Broadway, New York 1, N.Y.)

Filed Aug. 16, 1960, Ser. No. 61,778

Term of patent 7 years

(Cl. D48—24)

Fig. 1.

Fig. 2.

Fig. 3.

Fig. 4.

Fig. 5.

FIG. 1 is a top plan view of a bicycle lamp showing my new design;

FIG. 2 is a side elevational view thereof;

FIG. 3 is a bottom plan view thereof;

FIG. 4 is a front elevational view thereof; and

FIG. 5 is a rear elevational view thereof.

I claim:

The ornamental design of a bicycle lamp, substantially as shown.
